(57) **CLAIM**

The ornamental design for an attachment for a hair dryer, as shown and described.

DESCRIPTION

FIG. 1 is a perspective view of an attachment for a hair dryer according to the present invention;

FIG. 2 is a side view of the attachment for the hair dryer of FIG. 1, the opposite side being symmetric thereto;

FIG. 3 is a first end view of the attachment for the hair dryer of FIG. 1;

FIG. 4 is a second end view, opposite the first end view, of the attachment for the hair dryer of FIG. 1;

FIG. 5 is a first plan view of the attachment for the hair dryer of FIG. 1; and,

FIG. 6 is a second plan view, opposite the first plan view, of the attachment for the hair dryer of FIG. 1.
